A. J. RYAN

FELT TREATING MACHINE

Filed Oct. 2, 1920

INVENTOR:

INVENTOR:
Albert J. Ryan

BY *Albert Allée*

ATTORNEYS.

UNITED STATES PATENT OFFICE.

ALBERT J. RYAN, OF CINCINNATI, OHIO.

FELT-TREATING MACHINE.

Application filed October 2, 1920. Serial No. 414,236.

To all whom it may concern:

Be it known that I, ALBERT J. RYAN, a citizen of the United States, and a resident of Cincinnati, in the county of Hamilton and State of Ohio, have invented certain new and useful Improvements in Felt-Treating Machines, of which the following is a full, clear, and exact description, reference being had to the accompanying drawings, forming part of this specification.

My invention relates to machines for treating felt or the like with a hardening material which is impregnated into the felt, and upon cooling and drying leaves said felt in a stiff condition. Such felt is used in various ways, among others in the manufacture of box toes for shoes.

It is the object of my invention to impregnate felt or the like with quick hardening material in a continuous manner, so that a roll of the fabric may be passed through the machine and then stored. In the past it has been necessary or considered so, to dip the pieces of felt into the material and then lay them aside to dry, or else to employ a large number of expensive rolls and presses, which made for slow operation and great manufacturing cost.

According to my invention, a machine is provided which immediately after passing the material in a continuous strip through a very hot molten bath of the hardening medium, operates to force the medium into the body of the fabric, and at the same time remove the excess material and let it fall back into the bath.

My objects as above noted and other advantages to be described I accomplish by that certain construction and arrangement of parts to be hereinafter more specifically pointed out and claimed.

In the drawings,
45 Figure 1 is a sectional view of the device.

Figure 2 is a detail perspective taken through the impregnating and stripping device which is located directly over the bath, and receives the fabric before it strikes any other object.

The device is specially constructed so that sufficient heat can be maintained under the bath. Accordingly there is a foundation

1, in which is sunk a vat 2, beneath which 55 vat is set a gas burner 3, or other means of applying direct heat. There is also formed a chamber 4 alongside of the vat on the outside thereof, which permits the products of combustion to play against the sides 60 of said vat. The presence of the water vat 5 on the inside of the foundation prevents the use of a hot air chamber on the other side of the hot bath, unless the size of the machine is considerably expanded. The vat 65 2 has an idler roll 2^a set within it below the level of the molten material.

Mounted across the top of the vat 2 is a stripper and impregnator 6, formed preferably of two parts united together to form 70 a square with longitudinal openings 7 and 8 therein for the passage of the fabric, enforcing an angular path to said fabric after leaving the vat and before being led further.

Over the vat are further mounted a pair of standards 9, which mount an idler roll 10. The water vat 5 is sunk into the foundation as above noted, and has a roll 11 set therein below the level of the cooling or 80 hardening bath which is maintained therein.

Located just beyond the cooling bath are the calender rolls 12 and 13, which are driven by an actuated pulley 14, on a gear 85 15 on the large roll 12, which said gear 15 drives the small roll through a gear 16.

Beyond the one set of calender rolls the material may be assembled in whatever form is desired for storage, or be cut into the desired individual shapes, without further treatment.

With the machine as so constructed, the fabric is first passed down over the roll 2^a in the vat 2 and thence through the stripper and impregnator, thence over the 95 roll 10, down through the vat 5 and thence to the rolls 12, 13. The power to draw the cloth along is applied by the rolls 12, 13, and the cloth passes continuously through the machine.

Due to the construction of the vat 2, a flame and high temperature can be applied to the vat, which would not be practical if the same were heated by steam.

The exact form of the stripper and impregnator is not essential, as the features of it which are essential are the two slots through which the felt passes, being drawn

in an angular path through both of them, thus a piece of doubly split tubing, set with the slots out of line with the direct path from the vat idler roll 2^a to the roll 10 may be employed.

The position of this stripper device is also of importance as it acts on the cloth to both stretch, squeeze and scrape it, directly after it leaves the molten bath of the 10 hardener mixture. This therefore works the hardener into the fabric, before it has had time to be affected by the atmosphere and while it is still under the influence of the 15 heat of the vat. It follows, also, that the excess material wiped off of the fabric by this device will fall back into the vat.

While not desiring to limit my invention by describing my theory of the reason why my device will act to properly impregnate 20 a continuous strip of absorbent material or fabric with hardening compound, I may state that it is my understanding that the simultaneous stretching, squeezing and scraping of the fabric, caused by running 25 it on an angle to the path of its line of pull through a pair of slots, is what imparts the proper quality to my hardened felt. The saving in hardening material is very great, and the speed of treatment and thus saving 30 of labor is also a great economy. Furthermore, as above noted, my product is more uniform in texture, and less likely to be 35 over-filled with the gums and waxes of the hardener compound, thereby becoming inconvenient to handle during the manufacture of fine shoes.

The water bath may be used in the second vat or some fixing and cooling or hardening compound, so long as the impregnated felt 40 is not so sticky when it comes to the calen-

der rolls that it gums up and becomes unmanageable.

Having thus described my invention, what I claim as new and desire to secure by Letters Patent, is:

1. A machine for impregnating a continuous strip of fabric with hardening compound, which comprises means for drawing a strip of fabric through the machine, a vat for molten hardener compound, and a device 50 to receive the fabric located so as to drain into the vat, said device formed of a tubular body, having slots therein set in a plane transverse the direction of withdrawal of the fabric, whereby the compound is accumulated within the body and is scraped from the fabric, and worked into the fabric while same passes through said two slots. 55

2. A machine for impregnating a continuous strip of fabric with hardening compound, which comprises means for drawing a strip of fabric through the machine, a vat for molten hardener compound, and a device to receive the fabric located so as to drain 60 into the vat, said device formed of a tubular body, having slots therein set in a plane transverse the direction of withdrawal of the fabric, whereby the compound is accumulated within the body and is scraped from the fabric, and worked into the fabric while same passes through said two slots, another 65 vat for hardening compound, said means for drawing the strip through the machine, adapted to move the strip down through this vat for hardening the fabric prior to 70 accumulation thereof in a roll, said strip drawing means comprising a series of guiding rolls, and a drum onto which the completed piece is rolled. 75

ALBERT J. RYAN.
